Primary Examiner — Catherine Ho*(74) Attorney, Agent, or Firm* — Rumit Ranjit Kanakia(57) **CLAIM**

The ornamental design for a locker, as shown and described.

DESCRIPTION

FIG. 1 is a top perspective view of a locker showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of a locker in an open position;

FIG. 10 is a perspective view of a locker in another open position; and,

FIG. 11 is an enlarged view of the encircled area 11 in FIG. 1.

The broken lines shown in the drawings depict portions of the locker that form no part of the claimed design.

1 Claim, 11 Drawing Sheets(56)
